(57) CLAIM

The ornamental design for an exercise roller as shown and described.

DESCRIPTION

FIG. 1 is a top, front, left perspective view of an exercise roller showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the shaded areas define the bounds of the claimed design and form no part thereof. The broken lines depicting the remainder of the exercise roller form no part of the claimed design.

1 Claim, 5 Drawing Sheets
